UNITED STATES PATENT OFFICE

HARRY P. EDWARD, OF PORTLAND, OREGON

CONCEALED CABINET

Application filed April 29, 1929. Serial No. 358,987.

This invention relates to receptacles having a pivoted adjustable closure and more particularly to such receptacles as medicine cabinets. The principal object of the invention lies in the provision of a concealed wall cabinet the closure for which shall be a mirror which when closed shall give no indication whatsoever of the presence of the cabinet.

10 A second object of the invention lies in the provision of a new and useful hinge specifically adapted for use with a concealed cabinet. A further object of the invention lies in the combination between a mirror closure and a hinge together with optional means for forming a resilient holding means for securing the mirror in closed position. A still further object of the invention lies in the provision of a medicine cabinet to be 20 embedded in the wall with its front face flush with the surface of the wall and having a closure which will entirely hide the cabinet, such closure being adapted to have universal movement about the end of the bracket by which the closure is supported.

25 This application is a continuation in part of my application Serial No. 134,100, filed September 7, 1926.

At the present time medicine cabinets usually project from the wall altho there are numerous examples of cabinets which can be embedded in the wall flush with the surface but each of these latter type are somewhat unsightly due to the obvious presence 30 of the hinge which cannot be concealed and still have a straight hinge movement. The present invention contemplates the provision of an extremely attractive cabinet which has already gone far toward eliminating the old-fashioned medicine cabinet with its tell-tale mirror door usually quite unsightly and tolerated only because of the necessity for a cabinet in which to place objects which one does not care to leave around loose in the 40 bathroom.

The present concealed medicine cabinet gives no indication whatsoever of its utilitarian object for it is a thing of beauty in and of itself embodying a sheet of the finest 50 glass, beveled and engraved in Venetian

fashion with graceful wheel-cut designs. To replace the plain plate of the ordinary medicine cabinet with a Venetian mirror would generally not improve matters because of the unsymmetrical appearance necessary 55 when using a straight side hinge. In the present invention by substituting for the usual hinge an adjustable hinge and by making all parts of this hinge receivable within the cabinet a new era in medicine cabinets 60 is ushered in. While certain of the cabinets are made rectangular to meet a generally severe artistic treatment of the room most of the cabinets are shaped at the top, more usually having a graceful curve, often a 65 semi-circle, at the top, the mirror almost invariably being beveled and such fastening means as are used being hidden by ornamental glass studs.

In the drawings:—

70 Figure 1 shows a concealed medicine cabinet with its closure open and tilted forward at the top to give a convenient position for shaving.

Figure 2 shows the receptacle in central 75 cross section and shows the closure in an extreme position so as best to illustrate the relation of the parts.

Figure 3 is an end view of the clamp in 80 position of the mirror.

Figure 4 shows a slightly modified form of hinge designed to permit greater use of full width shelves.

Figures 5 and 6 show details.

The casing of the cabinet or receptacle is 85 denoted generally by the numeral 10 and is preferably made entirely of wood having a bottom 11, sides 12 and 13, with a top 14, here illustrated as an arch. The optional back 15 is preferably of somewhat thinner 90 wood usually cross-plyed or veneered as is the closure backing 16. While I might readily use a light metal spider for supporting the mirror 20, I much prefer the thin strong wood backing 16 as illustrated. This wood 95 backing is beveled and I prefer that it shall be of appreciably greater size than the front face of the cabinet, but slightly smaller than the mirror. By making the wood backing a trifle smaller than the inside dimensions of 100

the cabinet the back of the mirror can engage the wall but this is generally an inconvenience, as not only is there danger of marring the edges of the mirror but also it is 5 more difficult to open the receptacle hence I much prefer that the three-ply backing which is light and very strong shall extend substantially to the margin of the plate mirror.

10 Referring particularly to Figure 5 the mirror 20 is secured to the backing 16 by a screw 21 having a conical kerfed head 22 and engaging a nut 23 which is embedded in the backing and may be covered by a thin 15 sheet of veneer 25 of a higher priced wood if such be used, which obviously is optional. The glass is countersunk and I place a rubber gasket 26 between the head 22 and the mirror and then hide both the head and the 20 gasket by means of an ornamental glass stud 27 having a thin screw shank which is received into a hole tapped in the center of the screw head. In this manner there is nothing 25 on the face of the mirror to indicate that the device is anything other than an ordinary wall mirror.

At either the right hand or the left hand side of the receptacle depending upon its relation to the next adjacent wall I mount a 30 base 30 having two integral angular ends 31 which form bearing members for the vertical hinge end 32 of a bracket, the center portion of which is numbered 33 and is hereinafter called an arm. The free end of the 35 arm is bent upwardly forming a pivot 34 the active portion of which is slightly reduced so as to form a shoulder 37.

To the backing is secured a pair of saddles 40 having central concave portions 41 spaced 40 a trifle away from the backing and shaped to engage somewhat less than half the circumference of the reduced trunnion ends 42 of a cylindrical member 43 which I have termed the shaft. The two saddles 40 are 45 secured to the backing by means of screws 44 locked by one or more nuts 45 and passing thru the caps 47 receiving beyond them some adjusting means as for example the thumb nuts 48. Each saddle and its cooperating 50 cap or clip 47 constitute a clamp which may be adjusted so as to give any desired frictional resistance to movement of the shaft about a horizontal axis. The shaft 43 has a central bore 49 which receives fairly snugly 55 the reduced end, 34, the latter and the bore being sufficiently tight fitting so that the mirror will remain at any position to which it is turned about the vertical axis of the pivot 34.

60 A resilient clip 60 is placed near one edge of the closure and cooperates with a keeper 62 at the side 12 of the casing. This rather usual fastening is optional and if a single fastening means is to be used I much prefer 65 the clasp illustrated as located on the back-

ing near the hinge 32. This clasp consists of a pair of similar clips, identical by the way with the clip 60 and spaced apart so as to receive between them the horizontal portion or arm 33 of the bracket when the mirror is in closing position. The action is rather light but well sufficient to hold the mirror closed while yielding readily when the mirror is opened from the side distant from the hinge. In practice the clasp 64 70 and the clip 60 are both used and while this is preferred either fastening means may be used alone.

The casing 10 or embedded portion of the cabinet is fitted in the usual manner, preferably having shelves 65 of heavy plate glass which are spaced in such fashion, if they are to be the full depth of the casing, so as to clear the bottom of the bracket end 32 and to clear the tops of the thumb nuts 48. Frequently however some or all of the shelves 65 are made slightly shallower in which case they may be placed in any position desired. It might be noted in this connection that the extreme projection of any portion of the hinge into the casing is less than one inch which gives ample room for a shelf having a front to back depth of more than two inches.

95 The appearance of the plate glass mirror is much enhanced by the provision of a bevel such as 70 and the engraving of graceful wheel-cut designs on the back face of the mirror, for example, the flower, sprays and drops denoted as a whole by the numeral 71. 100 This leaves the entire surface of the mirror plane except for the studs 27 rendering it very easy to keep the mirror clean.

In the modification shown in Figure 4 the 105 parts are identical with the preferred form save that the downturned end 32 of the bracket is bent in reverse direction, i. e., upward, as denoted by the numeral 72. This portion of the bracket may carry a collar 73 which rests upon the lower bearing 74 110 while near the upper end of the hinge portion 72 of the bracket is a second, preferably independent, bearing 75. The advantage of 115 this form is that it affords greater room for full depth shelves.

While the location of the various parts is somewhat a matter of choice I find it preferable to have the shaft 43 located about centrally from top to bottom on the backing. While I might readily add a weight to the 120 backing so as to bring the center of gravity in line with the center of the shaft 43, I do not find this at all necessary as the mirror is reasonably heavy and the bracket itself quite sturdy so that the spacing of the shaft away from the hinge side of the cabinet is an advantage inasmuch as the placing of the center of gravity between the hinge end 32 of the bracket and the pivot end 34 of the same 125 bracket tends to provide the necessary bind- 130

ing between the shaft 43 and the pivot 34 which makes it possible to have these parts somewhat looser than is necessary where I have the pivot 34 alined with the center of 5 gravity of the closure.

In operation the casing 10 or wooden portion of the cabinet is embedded in the wall with the front faces of the portions 11, 12, 13 and 14 flush with the plaster line. The 10 backing 16 is approximately of the same thickness as the Venetian mirror 20 and being beveled as indicated at 76 it affords a convenient slot, so to speak, between the surface of the wall and the mirror so that the 15 closure can be opened from any edge, i. e., top, bottom, or either side. Generally it is slightly easier to open the cabinet by pulling outwardly at the top of the round portion of the mirror. With the edge of the bottom 11 20 acting as a fulcrum the shaft 43 turns about its horizontal axis in the clamps 41 and 47 and the closure is released simultaneously from the clips 60 and 64. With the closure in this position it may conveniently be adjusted by an outward pressure near the hinge 25 side. Those familiar with the concealed cabinet have no difficulty of any kind in handling the closure without ever touching the face of the mirror.

30 When fully or partly open the mirror has three movements giving it perfect freedom of action. The mirror may turn about the vertical axis of pivot 34; it may pivot about a vertical axis thru the hinge portion 32 of 25 the bracket and it may turn about a horizontal axis thru the center of the shaft 43. With the mirror at right angles to the surface of the wall all three of these axes will lie in a single plane. A striking feature of 40 the invention lies in the provision whereby the mirror may be closed by a direct push on the face of the mirror from any position. The closure will strike against the face of the casing and will be directed into closing 45 position with that edge of the casing as a fulcrum. This is a great convenience, in that the closing can always be done by one's hands or fingers on the highly polished 50 surface of the heavy mirror.

What I claim is:

1. In a device of the character described, a medicine cabinet to be embedded in a wall with its open front face flush with the surface thereof, a mirror closure shaped to the cabinet and of sufficient size to conceal the cabinet, a backing, means for securing the mirror to the backing, an arm hinged to the cabinet, a member mounted on said arm 55 to turn about a vertical axis thru the free end of the arm, and friction means adjustably securing the backing to the member with freedom for turning about a horizontal axis thru said member so that the mirror 60 when opened may be turned to any conven-

ient angle, said mirror in closed position engaging the wall to conceal the cabinet and hide the arm, the member, and the friction means, whereby an observer sees the closure mirror as if hung upon an unbroken wall 70 and resilient means carried by the backing to engage the arm to hold the parts in closed position.

2. In a concealed wall cabinet, a closure mirror therefor being larger than the face of the cabinet whereby to completely conceal the same when in closed position against the face of the cabinet, a hinge for securing the closure mirror to the cabinet comprising a rotatable supporting member the axis of which is horizontal, means for pivotally supporting the mirror on said member, a base to be secured within the cabinet and an arm receivable within the cabinet pivotally connected with the base and with said member thru parallel vertical axes, whereby when the mirror is pressed toward the cabinet it will engage the same and thereby be directed automatically into vertical closed position, irrespective of the tilt of the mirror when 85 last used.

3. The device of claim 2 in which there are a plurality of resilient clasping means for holding the mirror in shut position, said clasping means lying between the margins 90 from top to bottom of the horizontal axis of the member and the base whereby when the device is closed the mirror can be readily opened by pulling forwardly on the top of the mirror, releasing the clasps while using 95 the bottom of the mirror as a fulcrum.

4. In a device of the character described, a cabinet to be set in a wall opening with its open front face substantially flush with the surface of the wall, an ornamental mirror closure of sufficient size to conceal the wall opening, a backing, means for securing the mirror to the backing, an arm hinged to the cabinet, a member mounted on said arm 100 to turn about a vertical axis thru the free end of the arm, and friction means adjustably securing the backing to the member with freedom for turning about a horizontal axis thru said member so that the mirror when opened may be turned to any convenient angle; said mirror in closed position engaging the wall to conceal the cabinet and hide the arm, the member, and the friction means, whereby an observer sees the closure mirror as if hung upon an unbroken wall 115 110 as an independent ornamental wall attachment.

5. A bathroom cabinet consisting of a box having top, bottom, two sides and a back and adapted to be fitted into a vertical wall of 120 the bathroom flush with the vertical surface of the wall so that the front edges of the top, bottom, and sides of the box will be flush with said surface which will thus form a frame for the cabinet opening, a mirror cov- 130

er for the cabinet of such size as to completely cover the opening and said front edges, a bracket hinged to the mirror cover near one side and hinged to the cabinet at the other side, said bracket lying entirely within the cabinet space when the mirror closure is in closed position, and said mirror closure lying flush against the wall surface when in closed position.

5 6. In a concealed bathroom cabinet, an open face box-like body to be set in a wall opening, a mirror closure of such size as to completely hide the wall opening and a bracket hinged to the box-like body on one 15 vertical inside wall and hinged to the mirror closure near the opposite vertical wall, each hinged end of the bracket having a vertical axis so that the mirror closure in opening may move constantly parallel to the wall 20 surface and additional hinge means on the bracket whereby the closure when open may turn about a horizontal axis.

7. In a concealed wall cabinet, a cabinet having sides, a bottom and a top, a closure 25 larger than the face of the cabinet, a holder secured to one side of the cabinet, a bracket hinged to the holder, a vertical pivot at the free end of the bracket, a clamp on the closure and means receivable within the cabi- 30 net when the closure is against the plaster line of the wall for joining the pivot to the clamp so that the closure, when open, may be tilted about an axis thru said means, about a vertical axis thru said pivot, and about 35 the axis thru which the bracket swings in the holder.

8. In combination, a closure mirror, a concealed cabinet, a hinge for securing said closure mirror to said concealed cabinet comprising a shaft, means for pivotally supporting the mirror on the shaft, means secured within the cabinet, and an arm receivable within the cabinet pivotally connected with said second mentioned means and the shaft thru 45 parallel axes, the said shaft axis being horizontal and the parallel axes being vertical, whereby when the mirror is pressed toward the cabinet it will be directed automatically into vertical closed position by engagement 50 with the cabinet or its supporting wall, irrespective of the tilt of the mirror when last used.

In testimony whereof I affix my signature.
HARRY P. EDWARD.
